UNITED STATES PATENT OFFICE.

HERMAN H. HOLSCHER, OF WECOTA, SOUTH DAKOTA.

DEVICE FOR SECURING LOOSE MATERIAL IN BULK.

1,220,226.

Specification of Letters Patent. Patented Mar. 27, 1917.

Application filed March 18, 1914. Serial No. 825,661.

To all whom it may concern:

Be it known that I, HERMAN H. HOLSCHER, a citizen of the United States, residing at Wecota, in the county of Faulk, State of 5 South Dakota, have invented certain new and useful Improvements in Devices for Securing Loose Material in Bulk; and I do hereby declare the following to be a full, clear, and exact description of the invention, 10 such as will enable others skilled in the art to which it appertains to make and use the same.

This invention relates to devices for securing loose material in bulk and is particularly adapted for securing letters in packages for shipment in the mails.

The object of the invention resides in the provision of a device of this character which will enable letters and the like to be quickly 20 secured in packages for shipment through the mail without the necessity of tying same together and obviating the delay incident to such tying.

With the above and other objects in view 25 the invention consists in the details of construction and in the arrangement and combination of parts to be hereinafter more fully described and particularly pointed out in the appended claims.

30 In describing the invention in detail reference will be had to the accompanying drawings wherein like characters of reference denote corresponding parts in the several views, and in which—

35 Figure 1 is a perspective view of the carrier of the device;

Fig. 2, a perspective view of the carrier showing a plurality of letters secured in bulk thereby.

40 Referring to the drawings the carrier of the device is shown as comprising a body portion 10 in the form of a rectangular plate and having transverse rods 11 and 12 secured to respective ends thereof in any suitable manner, the ends of said rods projecting 45 beyond the side edges of the body portion.

10. The carrier further embodies a clamping element A including a bar 13 disposed

transversely of the body 10 and a plurality of arms 14 secured to said bar and running 50 longitudinally of the body. The ends of the bar 13 are connected to corresponding ends of the rod 12 by means of springs 15 and to corresponding ends of the rod 11 by means of springs 16, said springs 15 and 16 constantly tending to hold the clamping element 55 A disposed against the body 10.

In the use of the device the carrier is engaged in a loading or packing device which forms no part of this invention, so that the 60 element A is elevated above the base plate or body 10, and the material inserted in suitable quantity. When the desired quantity of material has been inserted, the carrier can be released to permit the body 10 and clamping element A to move in clamping relation. When the carrier is thus relieved, the 65 springs 15 and 16 will operate to secure the material between the body and clamping element in such a manner that the loose elements of the pack cannot slip out of the 70 bulk.

What is claimed is:—

1. A device for holding loose material comprising in combination, a body portion 75 comprising a base plate and transverse bars extending across and beyond the ends of the base plate, a transverse movable bar, retaining arms carried by the movable bar, and springs connecting the extremities of the 80 transverse-end bars and the movable bar.

2. A device for holding loose material comprising in combination, a base plate, transverse elements extended beyond the side of the base plate at its corners, a transverse 85 bar, longitudinal parallel arms supported by said transverse bar, and springs connecting the extremities of the transverse bar with said transverse elements beyond the sides of the base plate.

In testimony whereof, I affix my signature, in the presence of two witnesses.

HERMAN H. HOLSCHER.

Witnesses:

WILLIAM ALTWISE,
ELMER I. LEVANG.
